UNITED STATES PATENT OFFICE

JOHN B. OWENS, OF METUCHEN, NEW JERSEY.

TUNNEL-KILN.

1,251,273.

Specification of Letters Patent. Patented Dec. 25, 1912.

Application filed June 4, 1917. Serial No. 172,737.

To all whom it may concern:

Be it known that I, JOHN B. OWENS, a citizen of the United States, residing at Metuchen, county of Middlesex, and State 5 of New Jersey, have invented certain new and useful Improvements in Tunnel-Kilns, of which the following is a specification.

In the burning of clay materials it is of importance to regulate the rate of cooling of 10 the ware after maximum temperature has been reached. In a tunnel kiln the cooling or discharging end is always filled with cars and when air is admitted directly into the kiln on opening the doors at the discharge 15 end, it travels over these cars in succession from the coolest to the hottest and in a comparatively short time is practically as hot as the goods themselves which occurs before it reaches ware at a high enough temperature 20 to be damaged by direct contact with the air. If, however, an excess of cooling air be admitted, beyond what is naturally let into the tunnel when the doors are opened at the discharge end of the kiln, the temperature of 25 the cars at the discharge end will be reduced to such a point that they will no longer heat the air sufficiently to prevent damage to the ware at high temperature farther back in the kiln. For these, and other reasons, 30 cooling the burned ware by the admission of air directly into the kiln, is disadvantageous.

On the contrary, cooling of the ware by radiation of heat through the inner wall of 35 the kiln has none of the disadvantages of cooling by direct admission of air to the interior of the tunnel and, besides being desirable to perfect regulation, has the added advantage, when effected according to the 40 present invention, of furnishing an abundant supply of hot air which is utilized to effect a nearly perfect combustion of the fire or flame used for heating the kiln and assists in making the fire as nearly perfect an oxidizing fire as may be possible.

My present invention has for its object, therefore, the provision of improvements in a tunnel kiln, whereby the ware may be cooled after reaching maximum temperature, by direct radiation of heat from the ware through the inner wall of the kiln and the radiated heat utilized to heat outer air supplied to the oil or gas burner, or other fire, to aid combustion.

My invention is carried out by the provision of a double wall in the cooling end of the kiln beyond the furnace, considered in the direction of travel of the ware through the kiln, which is open to the air outside the kiln and is in communication with the furnace, for instance, by one or more ports adapted to feed the air to the oil or gas burner, or other fuel, used for heating the kiln. Any desired means may be employed for regulating the admission of the air to the space between the double walls and where the heated air is discharged to the burner or fuel; also, regulation may be had by a damper or the like for controlling the air admitted through the usual air-entraining opening of the furnace.

With the present invention, the draft or stack pulls the outer air in a downward direction between the double walls of the kiln and into the furnace. Heat radiated from the ware is absorbed by this inflowing air with a two-fold result: First, the ware is cooled because the radiated heat is taken away from it; second, the radiated heat raises the temperature of the inflowing air so that the air thus heated aids in obtaining as nearly perfect an oxidizing fire at the burner or in the furnace, as may be possible. None of the disadvantages of cooling the goods by direct admission of cool air into the tunnel result from the employment of the present invention, but, on the contrary, regulation of the cooling of the ware and of the supply of heated air to the furnace may be carried on as desired.

The embodiment of the invention herein-after described and shown in the accompanying drawing is susceptible of variation and is to be considered as merely illustrative of the invention.

I have shown and described, in addition to the present invention, cooling means such as substantially disclosed in my earlier application, Serial No. 109,551, filed July 15, 1916, to illustrate the independence of the present invention from such cooling means. In such cooling means the draft is upward in the walls of the kiln, due solely to heat conditions, whereas in the present invention the draft is downward due to the pull of the stack or fan that would pull or drive the air downward into the combustion chamber.

In the accompanying drawings:

Figure 1 is a half plan, half sectional view of so much of a tunnel kiln as will illustrate my invention; and

Fig. 2 a cross section on line 2—2 Fig. 1. The cars, having passed through a gradually increasing temperature in the kiln 1, approach the furnaces 2 as shown by the arrow *a*. The ware after being subjected to maximum heat when at the furnace 2, passes into the cooling portion 3 of the kiln, the cars finally emerging, at intervals, through the left hand end of the kiln which is closed by the door 4.

In my earlier application I have set forth cooling means comprising either a double wall or a plurality of independent air circulating ducts, the former arrangement being shown at 5, Fig. 1, and opening into the atmosphere at the top of the kiln by a number of ports 6. Outer air entering the space 5 at the bottom of the kiln, and also at points above the bottom, flows upwardly through the space and out through the ports 6. This air may be led into ducts and used for various heating operations, or, it may escape into the atmosphere. The circulation is upward and is a natural draft. The heat radiated from the goods into the space 5 is carried off and cooling is thus effected.

The space 5 and ports 6 constitute no part of the present invention, but are shown and described to distinguish my present improvements therefrom.

The kiln is provided with a double wall beyond the furnaces 2 as shown at 7, there being an air space 8 within said wall which is completely sealed from the space 5 by a partition 9 of brick so that there is no air communication or interdependence between the spaces 5 and 8. The space 8 is provided at its upper end with ports 10 opening out into the atmosphere. Dampers or bricks, certain ones of which are shown at 11, may be employed for regulating the intake of outer air into the ports 10. Were it not for the fact that the inner and outer walls of the kiln must be properly tied together to prevent the inner wall from bulging or giving way on the inside of the kiln, there would be no necessity for employing numerous ports 10 as the air space 8 could be provided with a single mouth for the entry of the air.

Joined to the walls of the furnaces 2 are air boxes 12 which are in communication with the respective spaces 8 by the openings 13. Dampers could be employed at the openings 13 for regulating the passage of the air from the spaces 8 into the boxes 12. Disposed within the boxes 12 and surrounded by the air space in said boxes, are the twyers 14 which communicate with the furnaces at 15 in such manner that the flame will be directed into the furnaces. The twyers have ports or openings 16 which communicate with the

interior of the air boxes. The openings 16 provide for an equal distribution of the air from the air box into the twyer 14.

Gas or oil burners 17 are located so that they will discharge into the twyers 14. In showing the invention in connection with oil or gas burners, I wish it understood that my invention is not limited thereto, as it may be carried out when coal is used as the fuel.

If desired, the admission of air into the mouth 18 of the twyer 14 may be controlled by a suitable damper.

The travel of the heat is as indicated by the arrows *b*, that is, in opposition to the direction of the travel of the cars *a*.

The draft at the stack, not shown, causes outer air to dive down through the ports 10 as indicated by the arrows and to pass through the openings 13 into air boxes 12, thence through ports 16 into twyers 14 to combine with the flames and air entrained through the mouths of the twyers. The relatively cool outer air absorbs the heat radiated from the ware which has passed the furnaces 2 with a two-fold result. First, the ware is cooled by being deprived of its heat through radiation, and, second, the air passing down through the spaces 8 has its temperature greatly heightened so that it combines with the flames from the burners 17 and the air entraining therewith to provide a more nearly perfect combustion in the furnace and cause the production of an oxidizing fire as near as may be possible.

In my present invention, the cooling of the ware by absorption of the heat radiated therefrom is accomplished by the stack draft and the passage of the air is downward as shown in Fig. 2, as distinguished from the natural draft, which is upward in the spaces 5. Furthermore, the same air which is used for absorbing the heat radiated from the ware, performs the additional function of supporting combustion due to the heat it obtains from the ware and while subject to the draft at the stack.

Having thus described my invention, what I claim as new and desire to secure by Letters Patent is:

1. A tunnel kiln having a furnace, and a diving air circulating space in its wall beyond the point of maximum heat derived from the furnace, said space having an air-receiving mouth at its upper part and being in communication with the furnace at its lower part, the air space being separated from the interior of the kiln by a single wall through which the heat radiated from the ware after the latter has passed the furnace and attained its maximum heat passes directly to said air space for absorption by the air in said space, the draft on the kiln causing air in said space to pass to the furnace, thereby cooling the ware and supply-

ing the furnace with heated air to support combustion.

2. A tunnel kiln having a furnace, a double wall provided with an air circulating space open to the outer air at its upper part, an air box with which said air circulating space communicates at a point lower down, a twyer open to the outer air and opening into the furnace, said twyer having ports 10 communicating with the air box, and a

burner adapted to discharge into the twyer, the stack draft on the kiln serving to draw outer air into the air box and twyer and into the furnace for the purpose of absorbing heat radiated from the goods and, also, 15 supporting combustion in the furnace.

In testimony whereof, I hereunto affix my signature.

JOHN B. OWENS.
